UNITED STATES PATENT OFFICE

172,411

MIXER BOWL

Joseph C. Wayne, Chicago, Ill.

Application September 9, 1953, Serial No. 26,748

Term of patent 14 years

(Cl. D44—1)

To all whom it may concern:

Be it known that I, Joseph C. Wayne, a citizen of the United States, residing at Chicago, in the county of Cook and State of Illinois, have invented a new, original, and ornamental Design for a Mixer Bowl, of which the following is a specification, reference being had to the accompanying drawings, forming a part thereof, in which:

I claim:

The ornamental design for a mixer bowl, as shown.
